UNITED STATES PATENT OFFICE.

EDWIN F. PIERCE, OF MILWAUKEE, WISCONSIN.

SHADE-HOLDER COUPLING.

No. 831,628.

Specification of Letters Patent.

Patented Sept. 25, 1906.

Application filed October 18, 1905. Renewed June 11, 1906. Serial No. 321,237.

To all whom it may concern:

Be it known that I, EDWIN F. PIERCE, a citizen of the United States, residing at the city of Milwaukee, county of Milwaukee, and 5 State of Wisconsin, have invented new and useful Improvements in Shade-Holder Couplings, of which the following is a specification.

My invention relates to improvements in devices for detachably coupling a shade to an incandescent-lamp fixture.

The object of my invention is not only to provide a device which will hold a shade more securely in place, but one which will always hold it in exactly the same relative position to the lamp-fixture.

It is a well-known fact that when the shade-supporting collars are coupled with a lamp-fixture by screw-threaded bearings the parts 20 are not always screwed up to their proper seat, when owing to the angle of the thread of the couplings the shades are sometimes left at an angle to the lamp-fixture, whereby such parts are not brought into their proper 25 relative position to each other, one side of the shade being thereby brought nearer to the lamp than the other, and is consequently heated more than the other side, when owing to the uneven expansion caused thereby the 30 shade is liable to be broken, while by my device it is obvious that it will be impossible to attach the couplings together at all otherwise than straight and in exactly the same relative position to each other, whereby the 35 liability of the shade becoming accidentally detached or broken by heat is avoided.

The construction of my invention is explained by reference to the accompanying drawings, in which—

40 Figure 1 represents a side view of the several parts of my device in connection with a lamp socket and shade as they appear when coupled together. Fig. 2 represents a side view of the lamp-socket of an ordinary incandescent lamp. Fig. 3 represents a side view of a coupling-collar removed from the socket. Fig. 4 represents the shade-supporting bracket; and Fig. 5 represents a side view of the part shown in Fig. 2 and the vertical section of the parts shown in Figs. 3 and 4, also coupled together.

Like parts are represented by the same reference-letters throughout the several views.

My invention comprises a socket A, provided at a slight distance from its lower end

with an annular bead B; a coupling-collar C, provided upon its lower side with a plurality of clamping-fingers D; a milled bead E, and a shade-supporting bracket F, provided with a plurality of coupling-fingers G and shade- 60 retaining screws H.

The diameter of the coupling-collar C is made slightly larger than the diameter of the bead B, so that it may be readily slipped over said bead. When desirous to couple 65 the said several parts together, the coupling-collar C is first moved over the bead B. When this is done, the bracket F is placed upon the socket A. The fingers G of the bracket F are curved outwardly at their centers, forming grooves I for the reception of the bead B, and said fingers G are sufficiently 70 resilient to spring over said bead B as the bracket F is placed upon the socket A. The fingers D are provided on their inner sides 75 with grooves J for the reception of the beads K, formed on the exterior surface of the fingers G. The space between the fingers D correspond in number with the fingers G, and when inserting the bracket in place the several 80 fingers G are brought beneath the coupling-collar C, midway between the fingers D thereof, whereby the respective grooves J are caused to register with the beads K of the fingers G when the coupling-collar C is 85 turned a partial revolution, whereby the grooves J of the several fingers D are brought over and caused to bear upon the several beads K of the fingers G, thereby securely holding said fingers G in place upon and 90 around the bead B of the socket, whereby all of said parts are securely coupled together in their proper relative position to each other, as indicated in Figs. 1 and 5. When desirous to disengage the shade-supporting bracket 95 F from the socket A, it is necessary simply to turn the coupling-collar C a partial revolution on its central axis in either direction, whereby the fingers D are again brought out of engagement with the beads K of the fingers G, when said bracket F, with the shade, may be readily removed from the socket.

The object of the chased bead E is to facilitate turning the coupling-collar C in either direction when desirous to couple the shade-supporting bracket to or uncouple it from the socket A. The bracket F is provided with a plurality of screws H, by which the shade K is secured thereto in the ordinary manner.

L represents an incandescent lamp which is coupled to the socket A in the ordinary manner.

Having thus described my invention, what I claim as new, and desire to secure by Letters Patent, is—

1. The combination of a lamp-socket provided near one end with an annular bead; a detachable coupling-collar provided with a plurality of fingers each of which fingers is provided with an internal groove for engagement with a bead formed on the shade-supporting bracket; a shade-supporting bracket provided with a plurality of fingers, said fingers being provided on their inner surfaces with grooves for engagement with an annular bead formed on the lamp-socket, and on their exterior surfaces with beads for engagement with the grooves formed on the inner surfaces of the fingers of the coupling-collar and means for securing a shade to said bracket.

2. The combination of a lamp-socket provided near one end with an annular bead; a

detachable coupling-collar provided with an annular bead to facilitate turning the same when coupling the several parts of my device together and a plurality of fingers each of which fingers is provided with an internal groove for engagement with a bead formed on the shade-supporting bracket; a shade-supporting bracket provided with a plurality of fingers, said fingers being provided on their inner surfaces with grooves for engagement with an annular bead formed on the lamp-socket, and on their exterior surfaces with beads for engagement with the grooves formed on the inner surfaces of the fingers of the coupling-collar and means for securing a shade to said bracket, all substantially as and for the purpose specified.

In testimony whereof I affix my signature in the presence of two witnesses.

EDWIN F. PIERCE
